UNITED STATES PATENT OFFICE.

EDWARD BALBACH, OF SPRINGFIELD, OHIO.

ELECTRICAL SIGNAL.

1,240,647.

Specification of Letters Patent. Patented Sept. 18, 1917.

Application filed September 21, 1916. Serial No. 121,394.

To all whom it may concern:

Be it known that I, EDWARD BALBACH, a citizen of the United States, residing at Springfield, in the county of Clark and 5 State of Ohio, have invented certain new and useful Improvements in Electrical Signals, of which the following is a specification.

My invention relates to improvements in 10 electric signals, and more particularly to a signal especially adapted for use on automobiles to indicate the course the driver intends to take or his intention to stop or back or any other information it may be 15 found desirable to convey.

The object of my invention is to provide 20 a signal of the character referred to which will be simple in construction and effective in operation and also one which can be easily and readily manipulated by the driver.

In the accompanying drawings:—

Figure 1 is a vertical section on the line 1—1 of Fig. 2.

Fig. 2 is a front elevation.

Fig. 3 is a side view of one of the operating drums.

Fig. 4 is a diagrammatic view of the electric circuits.

Referring to the drawings, A represents a casing which I employ to inclose the signaling devices which in the present case is shown provided with lugs, a, by means of which it may be attached to any suitable 35 point of support. The forward side of the casing is inclosed by a removable cover B which is secured thereto in any suitable way, and this cover is provided with an opening b, over which is secured a plate C 40 of glass or other transparent material; the plate C being secured in position by a retainer V.

The main operating device for the signals, 45 consists of a multiple or sectional solenoid, located at one side of the main casing which may be provided with an off-set portion or extension a² having a removable cover a² for the purpose; the respective sections of this solenoid being in the present case five 50 in number indicated by D¹, D², D³, D⁴ and D⁵. The core E of this solenoid has each end connected to a sprocket chain F which passes about the sprockets G, G¹, G² and G³, thus forming an endless operating device. 55 The sprockets G and G² are journaled on pins or studs M and M¹ secured to the walls

of the casing A, and one of the studs, such as M, preferably has means (not shown) for adjustment to give proper tension to the chain. Shafts L and L¹ extend transversely across the casing A near the top and bottom thereof, respectively, being journaled in the adjustable bearings N which are inserted from the outside of the casing A. Upon the upper shaft L is secured a drum H and loosely mounted upon the lower shaft is a second drum H¹, this drum H¹, however, being revoluble with said shaft L¹ through the medium of a coil spring P for the purpose hereinafter explained. The sprocket G² is connected to the upper shaft L, and the sprocket G³ is connected to the lower shaft L¹, so that these sprockets will impart rotary movement to the shafts when the solenoid is energized. The spiral spring P before referred to has one of its ends connected to the drum H¹ by the pin R, the other end of the spring being fastened to a collar W which is secured to the shaft L¹ by the pin Q; the collar being secured to the shaft by the set-screw S so that the tension of the spring may be adjusted for the purpose of maintaining the signal ribbon or tape O taut, this ribbon being wound upon and secured to the respective drums; 85 the tendency of the spring P being to revolve the drum H¹ about the shaft L¹, the ribbon, however, tending to resist revolution so that a tension will be maintained upon the ribbon. This ribbon is provided with any desirable signals such as "Back," "Right," "Left," "Stop" and "Fore." I prefer to have the characters indicating the signals opaque or black, while the ribbon will be of a transparent or translucent material such as celluloid. 95

For the purpose of illuminating the signals, an electric lamp I is mounted within a reflector J and supported from the casing A by a bracket K; this lamp extending to a point immediately behind the ribbon O and in line with the opening b.

Referring to Fig. 4, T represents a battery and 1 and 2 conductors leading from its terminals, the conductor 1 being connected to each of the solenoid sections and also to one terminal of the lamp, while the conductor 2 leads to a movable switch member U. Associated with this switch member is a series of contacts, one for each solenoid section, the contacts being connected with their corresponding sections by the 105 110

wires 3, 4, 5, 6, and 7. The movable switch member is also designed to close the lamp circuit through the wire 8 which leads to the other terminal of the lamp.

- 5 When in normal position the core E will be in central position with respect to the section D¹ and the signal "Fore" will be displayed. If the switch member U is moved to the first contact, or the contact 10 which is associated with the section D¹ of the solenoid, that section is energized but the core E will remain in its normal position. If the switch lever is now moved to the next contact, the one designated by D², 15 that section will be energized and D¹ de-energized, causing the core to center itself with respect to the section D² so as to display the signal "Stop". By moving the switch member U to any of the other contacts, the core will be caused to center itself 20 with respect to the solenoid section whose contact is closed and thus cause the desired signal to be displayed. It should be explained that the contact points are so spaced 25 that the switch member U cannot leave one contact point before engaging the next point so as to give a uniform movement to the core. To bring the signal ribbon back to its normal position, it is only necessary 30 to reverse the operation by throwing the movable switch back to its normal position. It will also be noted that so soon as the movable switch is thrown in circuit with the first contact corresponding to the con- 35 ductor 3, the lighting circuit will be established and this circuit will remain established throughout all the different points of contact; the position of the switch shown in the drawing being the one for day 40 straight ahead driving in which position the light, of course, is out of commission.

Having thus described my invention, I claim:—

1. In an electric signaling device, a main 45 casing, a sectional solenoid having a core movable in either direction from one section to another by the energization of said sections, a flexible ribbon having a series of signals thereon, rotatable drums to which 50 said ribbon is connected, and flexible connections between the respective drums and the ends of the core of said solenoid whereby said solenoid will rotate said drums in either direction.
- 55 2. In an electric signaling device, a sec-

tional solenoid having a core movable in either direction from one section to another by the energization of said sections, a flexible ribbon having a plurality of signals, drums to which the respective ends of said ribbon are connected, flexible connections between the respective drums and the ends of the core of said solenoid whereby said drums may be rotated in either direction, and illuminating means for said signals. 60 65

3. In an electric signaling device, a sectional solenoid having a core movable in either direction from one section to another by the energization of said section, a pair of drums, flexible connections between the drums and the ends of the core of said solenoid whereby said drums may be rotated in either direction, a flexible ribbon on said drums having a plurality of signals thereon, and means for maintaining said 70 75 ribbon taut.

4. In an electric signaling device, a sectional solenoid together with means for energizing the respective sections to cause the core thereof to move in either direction 80 from one section to another, a pair of drums, a ribbon on said drums having a plurality of signals, sprocket wheels connected to the respective drums and a sprocket chain connected to the respective ends of the core of 85 said solenoid and passing over said sprocket wheels to form an endless driving connection whereby said drums may be rotated in either direction.

5. In an electric signaling device, a sectional solenoid together with means for energizing the respective sections thereof to cause the core of said solenoid to move in either direction from one section to another, a pair of drums, a flexible ribbon 90 having a plurality of signals on said drums, a sprocket wheel connected to each drum, a pair of idle sprocket wheels, and sprocket chains passing about the respective sprocket wheels and connected to the respective ends 95 of the core of said solenoid to form a continuous driving connection whereby the drums may be rotated in either direction. 100

In testimony whereof, I have hereunto set my hand this 16th day of September, 105 1916.

EDWARD BALBACH.
